UNITED STATES PATENT OFFICE.

DAMON GREENLEAF AND JOSEPH H. CROSBY, JR., OF JACKSONVILLE,
FLORIDA.

DESIGN FOR A SPOON.

SPECIFICATION forming part of Design No. 22,717, dated August 22, 1893.

Application filed July 20, 1893. Serial No. 481,058. Term of patent 7 years.

To all whom it may concern:

Be it known that we, DAMON GREENLEAF and JOSEPH H. CROSBY, Jr., citizens of the United States, residing at Jacksonville, in the 5 county of Duval and State of Florida, have invented and produced a new and original Design for Spoons, of which the following is a specification, reference being had to the accompanying drawing, illustrating the same.

10 Our invention relates to an improved design for spoons, and more particularly to bonbon spoons.

15 The accompanying drawing represents a bonbon spoon made in accordance with our design.

In the accompanying drawing, A represents the handle of the spoon, which is made to represent scrolls *a* and flowers *b*, the end of the handle nearest the bowl *B* of the spoon being

represented as terminating in two scrolls *c*, *c*. 20 Between the bowl *B* and the handle *A*, a crown *C* is represented. The bowl *B* of the spoon is divided into four panels, and in two of said panels castles *d* are represented, and in the other two animals *e* are illustrated. At the 25 edge of the bowl *B*, a wreath or decorated chain *f* is located and made in two parts with a cross *g* between the parts, and adjacent to the cross an animal *h* is represented.

What we claim is—

30 The design for a spoon herein shown and described.

DAMON GREENLEAF.
